FILM SPLICER

Philip Baia, Highland Park, Mich.

Application June 20, 1944, Serial No. 541,193

2 Claims. (Cl. 154—42)

This invention relates to improvements in splicers, and refers particularly to splicers for motion picture film. The invention aims, among other things, to provide a splicer for holding the two ends of the film to be joined together; for trimming the two ends prior to making the joint; for scraping the emulsion from one of the ends where adhesive is to be applied; and for holding the two ends of the film in intimate contact after the adhesive has been applied and during the setting of the joint.

Another object of the invention is to provide a splicer having a fixed base, a stationary plate thereon, and a hinge pin extending the full width of the base which extends through downturned ears formed on opposite sides of two clamping plates and a supporting plate in such a manner that the said pin affords rigid and ample support for the movable plates to insure accuracy of movement.

A further object of the invention is to provide a splicer having a scraper mounted for movement on one of the clamping plates so that when the scraper is turned in one direction it may be employed to contact one side of a piece of film and remove the emulsion therefrom prior to an adhesive being applied thereto; moreover the scraper is so arranged that it may be turned back out of the way when not in use.

Having thus briefly stated some of the objects and advantages of the invention I will now proceed to describe it in detail with the aid of the accompanying drawings, in which:

Figure 1 illustrates a plan view of the invention with the clamping plates and the supporting plate turned vertically upward.

Figure 2 is a view similar to Figure 1 but showing the clamping plate over the stationary plate downturned and a piece of film engaged between the said plates.

Figure 3 is similar to Figure 2 except that the scraper is shown in operative position.

Figure 4 is another plan view showing the supporting plate and both the clamping plates downturned in position to support two film ends in overlapping relation while the adhesive is drying.

Figure 5 is a plan view showing the clamping plates turned vertically upward for the removal of the film after the joint has been made.

Figures 6, 7 and 8 are sections on the lines 6—6, 7—7 and 8—8 respectively of Figure 4, the sections shown in Figures 7 and 8 being enlarged.

Figure 9 is a section on the line 9—9 of Figure 8.

Referring to the drawings, 1 designates a base having downturned sides 2 the lower extremities of which have outwardly projecting flanges 3 which rest upon and are suitably secured to a subbase 4. The ends 5 of the base 1 are also downturned and terminate above the subbase. Extending through and between the downturned sides 2 adjacent the back of the splicer is a hinge pin 6 the ends of which are usually riveted over against the outer faces of the sides 2 to hold the pin rigid and immovable.

Formed in the base 1 intermediately of its length and width is an opening 7. Projecting upwardly from the top of the base along one lateral margin are two spaced guides 8 and 9, and projecting upwardly along a portion of the other lateral margin is a vertical guide 10. The guides 8 and 9 form stops against which the outer margin of the stationary plate 11 rests 15 which extends partway across the base 1 and is welded or otherwise suitably secured thereon. The inner margin of the plate 11 is positioned over the opening 7, and provided on the said plate are transversely aligned projections 11a to 20 engage conventional perforations B formed in one piece A of the film to be spliced.

A clamping plate 12 is provided on opposite sides with ears 13 through which the hinge pin 6 extends thereby mounting the said plate pivotally with its outer ear contiguous to the inner face of one of the sides 2 and its inner ear encircling the hinge pin substantially centrally of its length. The width of the clamping plate 12 is such that when it is downturned to bear upon 25 the top of the stationary plate 11 its outer lateral margin rests against the guide 9, and its opposite margin is inwardly spaced from and parallel with the inner margin of the said stationary plate so that a ledge 30 of uniform width projects along the inner edge of the said stationary plate. Formed through the plate 12 are openings 12a into which the projections 11a extend when the said plate is downturned to hold the 30 length of film A immovable between the two plates 11 and 12.

A second clamping plate 14 having downturned ears 15 through which the hinge pin 6 extends is also pivoted on the latter and is so positioned that the outer face of one of the ears 15 lies contiguous to the outer face of the inner ear 13 and the outer face of the other ear 15 lies against the inner face of one of the sides 2. Thus the plates 12 and 14 are held against axial movement along the hinge pin by contact of their ears with one another and 35 with the inner faces of the sides 2. A pivoted

supporting plate 16 adapted to rest upon the base 1 beneath the clamping plate 14 has ears 17 through which the hinge pin 6 extends; the outer faces of these ears 17 are contiguous to the inner faces of the ears 15.

The width of the bearing plate 16 is such that when it is downturned it rests upon the base 1 in horizontal alignment with the stationary plate 11 with its inner lateral margin adjacent and in shearing engagement with the inner lateral margin of the stationary plate and its opposite margin adjacent the guide 10. The width of the second clamping plate 14 is such that one lateral margin, when the plate is downturned, moves in substantial contact with the said guide 10 and its opposite margin is parallel and in shearing engagement with the adjacent side of the plate 12. Extending upwardly from the supporting plate 16 are transversely spaced projections 16a, in alignment with the projections 11a when the said plate 16 is resting upon the base 1, and formed through the clamping plate 14 are openings 14a to receive the said projections. The latter are to engage conventional perforations D in a length of film C and retain the latter in alignment with the length of film A. Due to the lateral spacing of the two pairs of shearing edges of the plates 11 and 16, and 12 and 14, the film ends when cut as herein-after described are in overlapping relation.

Pivoted on the inner face of the downturned end 5 remote from the hinge pin 6 are two latches 20 and 21 which project upwardly through openings 22 and 23 formed through the base 1. The latch 20 is also adapted to extend through an opening 24 in the clamping plate 12 to engage the upper face of the latter and retain it in contact with the stationary plate 11. The latch 21 is adapted to project through aligned openings 25 and 26 formed through the supporting plate 16 and the clamping plate 14 respectively and engages the upper face of the latter to hold the two plates in contact with one another and in horizontal alignment with the plates 12 and 11 respectively. Mounted intermediately of its length on the underside of the base 1 is a resilient member 27 having laterally projecting arms 28 each of which engages a projection 20a or 21a on one of the latches 20 or 21 and tends to turn its latch about its pivot axis to engage the plate 12 or 14. To release the plates it is merely necessary to move the latches pivotally outward.

Projecting upwardly from the clamping plate 12 are two spaced brackets 31 to which opposite extremities of a rod 32 extending at right angles to the hinge pin 6 are secured. Mounted for axial and pivotal movement on the rod 32 is a substantially U-shaped mounting 33 having a scraper 34 secured thereon and facing outwardly from the rod 32. When the mounting is turned to the position shown in Figure 3 the scraper may be reciprocated axially on the rod 32 along the ledge 30 to remove the emulsion from the piece of film A resting thereon, for removal of the emulsion is necessary in order for an adhesive to firmly adhere thereto. After the scraper has served its purpose it is moved pivotally about the axis of the rod 32 to a position shown in Figures 2 and 4 where it is out of the way.

The operation of the invention is briefly as follows: One film end A is placed on the stationary plate 11 with the projection 11a extending through the perforations B and the end of the film projecting laterally inward somewhat beyond the end of the plate 11. The clamping plate 12 is then moved down and engaged by the latch 20,

Then the bearing plate 16 is moved pivotally downward into contact with the base 1. During the completion of this movement the end of the film A is sheared off between the adjacent faces of the stationary plate 11 and the supporting plate 16. The scraper 34 is then employed in the manner already described. The other film end C is then engaged between the supporting plate 16 and the clamping plate 14 with the projections 16a extending through perforations D in the film so that the two film ends are held in alignment. Meanwhile downward movement of the clamping plate 14 onto the supporting plate 16 when the latter is resting upon the base 1 shears off the end of the film C between the adjacent edges of the plates 14 and 12. After adhesive has been applied to the upper side of the film end A resting upon the ledge 30 and the plates 16 and 14 have been moved down onto the base 1 the latches 20 and 21 plus the overlapping relation of the clamping plate 14 relative to the stationary plate 11 insures that the ends of the two pieces of film A and C are held in intimate contact while the adhesive dries.

While in the foregoing the preferred embodiment of the invention has been described and shown it is understood that the invention is susceptible to such alterations and modifications as fall within the scope of the appended claims.

What I claim is:

1. A film splicer including a base, a hinge pin mounted thereon and extending across one side thereof, a stationary plate fixed on the base and extending partway across it, a supporting plate pivoted on the pin adapted to be downturned to rest upon the base with one margin extending at right angles to the pin axis contiguous to the inner lateral margin of the stationary plate, two clamping plates pivoted on said pin one adapted to be downturned onto the stationary plate and the other onto the supporting plate, said clamping plates having their adjacent margins contiguous when said plates are in transverse alignment, the last named adjacent margins being transversely stepped relative to the contiguous margins of the stationary and supporting plates, there being two sets of openings, one set in the base and clamping plate adjacent the stationary plate and the other set being in the base, supporting plate and adjacent clamping plate, and latches, respectively pivoted on the underside of the base adjacent the sets of registering openings to extend through each registering set of openings, a spring mounted intermediately of its length on the underside of the base, and a projection on each latch engaged by one extremity of the spring whereby the spring tends to move said latches pivotally to engage the upper faces of the clamping plates and hold the latter in firm engagement with the plates beneath them.

2. In a film splicer, the combination of a base having vertical downturned walls along opposite sides which extend rearwardly beyond said base, a hinge pin supported at its extremities by the rearwardly projecting portions of said walls, the front extremity of said base being also downturned to form a front wall, a stationary plate fixed upon said base and extending partway across the latter, a supporting plate pivoted on said pin to be downturned onto the other side of the base with one longitudinal margin contiguous to the inner lateral margin of the stationary plate, two clamping plates pivoted on the hinge pin one adapted to be downturned onto the stationary plate and the other onto the supporting

plate, the adjacent edges of the clamping plates being contiguous when said plates are in transverse alignment, the contiguous margins of the clamping plates being laterally stepped relative to the contiguous margins of the supporting and stationary plates, the pivot mountings of the clamping plates and the supporting plate being positioned relative to one another and to said downturned opposite walls to prevent axial movement of the plates relative to one another, there being two sets of openings, one set in the base and clamping plate adjacent the stationary plate and the other set being in the base, supporting plate and adjacent clamping plate, a spring mounted intermediately of its length on 15

the underside of the base, latches pivoted on the inner face of the front wall, one latch extending through the registering openings in the base and the clamping plate and being adapted to hold said clamping plate in firm engagement with the stationary plate, the other latch extending through the other opening in the base and being adapted to project through the openings in the supporting plate and the other clamping plate to hold the latter in firm engagement with said supporting plate, and a projection on each latch, said projections being engaged by opposite ends of the spring whereby said latches are urged toward their clamping plate engaging positions.

PHILIP BAILA.
